UNITED STATES PATENT OFFICE.

LAWRENCE W. LUELLEN, OF MOUNTAIN LAKES, NEW JERSEY, ASSIGNOR TO INDIVIDUAL DRINKING CUP COMPANY, OF NEW YORK, N. Y., A CORPORATION OF MAINE.

RECEPTACLE.

1,273,891.

Specification of Letters Patent. Patented July 30, 1918.

Application filed July 16, 1918. Serial No. 779,931.

To all whom it may concern:

Be it known that I, LAWRENCE W. LUELLEN, a citizen of the United States, residing at Mountain Lakes, county of Morris, and 5 State of New Jersey, have invented certain new and useful Improvements in Receptacles, of which the following is a specification.

This invention relates to receptacles and 10 particularly to cups or containers of paper or other light and fragile material and it is designed to provide a temporary vessel which while strong and serviceable can be very cheaply constructed, so that it may be 15 economically discarded after a single use. Such receptacles have in recent years come in to quite general use as drinking cups for use in public places and have met with high approval from medical authorities as 20 providing the only safe and satisfactory substitute for the dangerous common public drinking cup. The present invention provides an improved structure, which is strong and convenient, comfortable to drink from 25 and in which a plurality of cups can be stacked in properly spaced nested relation so as to be placed within and readily delivered from a dispensing device. At the same time a very light material can be utilized 30 for making the receptacle so that the cost of the same is low and permitting the receptacle to be easily crushed or destroyed by the user so as to prevent its being again employed. For the latter purpose the receptacle 35 may also be so constructed that it will be self-destructible and will become useless at a suitable interval after it has been first filled with the liquid which it is designed to contain.

40 In the accompanying drawing which forms a part of this specification—

Figure 1 is a side elevation of a cup embodying one form of the invention;

Fig. 2 is a vertical section through the cup 45 on an enlarged scale;

Fig. 3 is a fragmentary sectional view through the upper edge of the cup on a still further enlarged scale; and

Fig. 4 is a similar sectional view through 50 the lower portion of the cup.

Referring to the drawing in detail, the numeral 1 designates the cup, the side wall of which preferably comprises a single piece of paper 2, formed into suitable shape, preferably that of a truncated cone. This truncated cone may be formed in any suitable

manner, as for instance by rolling up a flat sheet of paper of proper shape and pasting or otherwise joining its edges. The bottom of the cup is formed of a disk 3, preferably of paper or paste board somewhat heavier than the side wall 2. This bottom is secured in position, in some suitable manner, preferably as shown in Figs. 2 and 4. In practice the bottom is forced into the truncated cone until it fits tightly therein and stretches the paper outwardly around its edges as indicated at 4, the bottom being thus partly held in position by the tension of the side wall. The lower edge of the part 2 is then 50 bent or spun up inside of the side wall to form a leg 5. The upper edge of this leg is preferably curled or turned outwardly under the bottom disk 3, as indicated at 6 the leg thus serving as a support for the bottom 55 disk. An inwardly projecting rib or crease 7 is then pressed in the side wall of the cup, above the bottom 3, so as to form a shoulder for holding the same in position upon the leg 5. The leg 5 is preferably not folded 60 closely against the downwardly projecting portion 8 of the side wall 2, but a space 9 is left between these parts. The edge of the curled over portion 6 preferably abuts against the side wall so as to hold the parts 65 5 and 8 spaced apart. This construction provides a downwardly projecting tubular supporting flange at the bottom of the cup of great rigidity and permits the use of a very light material for the side wall 2. This 70 supporting flange not only provides a support for the cup when in use, but serves the important function of spacing the cups apart when nested as for shipment or to be placed in a dispensing apparatus. The use 75 of this flange when the cups are nested holds them relatively free from each other and prevents them from becoming wedged into each other in a manner to interfere with their ready separation and also holds the 80 upper edges of the cups in regular spaced relation, so as to permit the rims of successive cups to be properly engaged by the engaging or gripping portions of the dispensing apparatus in a well understood 85 manner. The hollow construction shown for this flange provides greater rigidity than if the leg 5 were simply bent back closely against the outer portion 8, does not require the use of additional stock, as where several 90 thicknesses of material are folded back and forth or rolled up into a tight roll and is 95 100 105 110

also easier to manufacture than either of such constructions. It also provides a rigid flange of greater depth than can be readily secured by rolling the material into a solid bead and in fact permits the making of the flange of any desired depth to secure the most satisfactory spacing of the nested cups. Moreover, in the construction shown, while the bottom 3 is firmly held in position, it is 10 not locked to the side wall as in constructions where the bottom is provided with a flange which is rolled into a bead with the lower edge of the side wall, so that when the cup is crushed after use the bottom will 15 be loosened or separated from the side wall and thus effectually prevent the re-use of the cup. The hollow formation of the flange performs the further function of catching any slight leakage of the contents of the receptacle around the edge of the bottom disk, as such slight leakage as may occur will 20 run down into the space between the side wall and leg 5 where it will do no harm, before it will run over the curved portion 6 and escape at the bottom of the cup in a 25 manner to be noticeable. The cup shown is provided with a beaded upper edge, or rim, of novel construction, which will now be described. This novel beaded edge is preferably 30 used in connection with the novel bottom construction described, although it will be understood that either of these features may be separately embodied in a receptacle without departing from the invention. Referring particularly to Figs. 2 and 35 3, it will be seen that the upper edge of the side wall of the cup is rolled over to form a curved lip or roll 10 of comparatively large radius, the edge of this rolled over portion being bent up within the roll, as indicated 40 at 11. This bent up portion is preferably given a slight reverse curvature, as indicated at 12, and its edge caused to abut against the under-side of the roll 10. This 45 construction provides a smooth roll edge, which is attractive in appearance, comfortable to the lips of the user when drinking from the cup and which gives the maximum of rigidity to the rim of the cup for the 50 material employed. Experience has shown that the construction described is much stronger and stiffer than where the edge of the cup is simply rolled over to form a roll or bead of substantially circular cross-section, the reason for this probably lying in 55 the fact that the novel bead or rim has no tendency to unroll or flatten into elliptical form when bent, but can only give by stretching or breaking. When the rim is bent the 60 edge portion 11 abuts against the under side of roll 10 and thus braces the roll so as to prevent material change in the section thereof. The several curvatures of the bead or roll mutually interact and brace each other 65 so that the full strength of every portion

of the rim is utilized. The width of the roll is much greater than can be secured where the paper is attempted to be rolled into a solid bead and therefore a greater resistance to distortion is secured than with such a construction. The present construction is also much easier to manufacture than a solid, rolled bead.

The receptacle herein disclosed may be treated with paraffin or other water-proofing or stiffening material if desired, but this is unnecessary as the parts of the vessel are firmly held together without the use of such material and the vessel is sufficiently rigid for satisfactory use, even though made of very light flexible stock. When the receptacle is to be employed as an individual drinking cup, the use of paraffin or other coating material is preferably avoided as it not only adds to the cost of construction, 85 but is objectionable for a temporary cup, as it invites the preservation of the same for repeated use. By forming the cup of uncoated paper it is made self-destructible, for within a few minutes after the cup is once filled with liquid, the paper softens and the cup becomes unfit for further use. This self-destructible feature of the receptacle may also be secured, whether the cup be made of uncoated, or coated or water-proof material; by securing together the edges of the side-wall or other parts of the cup with a paste or binder capable of being softened or weakened by the material which the receptacle is to contain. Thus in the form of the cup illustrated, by securing the edges of the paper 2 together by means of a suitable soluble binder, the seam can be made to open a short time after the cup has been once filled with water and thus the continued or repeated use of the cup is absolutely prevented. In this manner the cup becomes when subjected to use self-destructible and it is with this meaning that I have used this term in the annexed claims. By properly selecting the paste, the period for which the cup can be rendered serviceable can be practically determined in advance. This principle is applicable to receptacles of any construction which are held in shape or in which parts are held together by a paste or binder.

It is obvious that the constructural features disclosed may be employed in receptacles of other nature and form from that illustrated in the drawings.

Having thus described my invention what I claim as new and desire to secure by Letters Patent is:

1. As a new article of manufacture a paper cup having a rim comprising an outwardly rolled portion, the edge of which is bent up within said roll and into engagement with the underside of the top thereof.
2. As a new article of manufacture a

nestable drinking cup having a side-wall portion within which, near the lower end thereof, is fitted a bottom, the edge of said side-wall portion being bent up beneath said bottom to form a supporting leg therefor, said supporting leg being spaced from the side-wall so as to form a hollow supporting flange for the receptacle, said side-wall portion having a shoulder formed therein above 5 said bottom for holding the same in place, and a rim at the upper end of said side-wall portion comprising an outwardly rolled portion, the edge of which is bent up within said roll and spaced from the outer surface of said side-wall portion. 10 15 20 25

3. A receptacle having a side wall portion within which, near the lower end thereof, is fixed a bottom, the edge of said side wall portion being turned inwardly to form a supporting flange for said bottom, said flange being transversely loop shaped, said side wall portion having a shoulder formed therein adjacent to said bottom for holding the same in place, and a rim at the upper end of said side wall portion comprising an outwardly rolled portion, the edge of which

is bent upon said wall and spaced from the outer surface of said side wall portion.

4. A receptacle comprising a body portion having a turned over edge, said edge having 30 a transversely loop shaped formation, one side of said loop being substantially straight, while the opposite side is bowed inwardly, with the edge turned outwardly, whereby a yieldable supporting rim is 35 formed at the point of closure of said loop.

5. A receptacle comprising a body-portion having a turned over edge, said edge having a transversely loop shaped formation, one side of said loop being substantially straight, 40 while the opposite side is bowed inwardly, with the edge turned outwardly, whereby a yieldable supporting rim is formed at the point of closure of said loop capable of sustaining a considerable downward pressure. 45

In witness whereof I have hereunto set my hand in the presence of two subscribing witnesses.
